UNITED STATES PATENT OFFICE.

CHARLES F. COX, OF BRIDGETON, NEW JERSEY.

PROCESS FOR THE MANUFACTURE OF HOLLOW GLASSWARE.

No. 851,163.

Specification of Letters Patent.

Patented April 23, 1907.

Application filed November 18, 1905. Serial No. 287,917.

To all whom it may concern:

Be it known that I, CHARLES F. COX, a citizen of the United States, and a resident of Bridgeton, county of Cumberland, and State 5 of New Jersey, have invented a certain new and useful Process for the Manufacture of Hollow Glassware, of which the following is a specification.

My invention relates to processes for the manufacture of hollow glassware and has for its object to provide a simple and efficient method for manufacturing such glassware.

The invention will be fully described hereinafter and the features of novelty will be 15 pointed out in the appended claims.

Reference is to be had to the accompanying drawings, in which

Figure 1 is a sectional elevation of a portion of a machine for manufacturing glassware according to my invention; Fig. 2 is a 20 sectional elevation showing the parts in a different position; Fig. 3 is an enlarged detail section thereof; Fig. 4 is a similar view with the mechanism in a different position; Fig. 5 is a horizontal section taken on the line 5—5 25 of Fig. 4; Fig. 6 is an elevation with parts in section showing the apparatus in conjunction with the means for raising and lowering the blank mould; Figs. 7 and 8 are top views 30 of the mechanism for opening the vacuum finishing mould showing the same in two different positions; Figs. 9 and 10 are respectively a top view with parts in section, and a sectional elevation of the mechanism for raising 35 and lowering the blank mould, and for opening and closing the same; Fig. 11 is a sectional elevation of a slightly modified construction; and Fig. 12 is a section on line 12—12 of Fig. 10.

40 A represents a cylinder provided at its upper end with a reduced bore B, with which it is connected by a by-pass B'; said cylinder is supported upon a table C. The cylinder A is connected with a convenient compressed air 45 supply at D, and the reduced portion B is also connected with such source of compressed air at E. A piston F, secured to a hollow piston rod G having openings G', is adapted to work in the cylinder A, in the 50 manner to be more fully described herein- after. To the free end of this piston rod G is secured as by a screw thread a head H, which in turn carries a neck mould I. A second piston J, is secured to a piston rod K located in- 55 side of the hollow piston rod G. This second

piston rod K carries at its free end a valve cage L which snugly fits the inside of the piston rod G and has secured to it a plunger M. A valve N is located inside of the valve cage L and engages a seat O on said cage, which is further provided with openings P and Q. A stuffing box R is supported by the table C, and is provided with a chamber R' connected by a pipe R² with a vacuum pump of any well known description.

60 S is a mould casing carrying the perforated finishing mould S'. The mould casing S and mould S' are made in two sections and are capable of being opened and closed as shown in Figs. 1 and 2. This opening and closing of the finishing mould may be accomplished in any convenient manner, as by supporting each section of the mould and mould casing on swinging arms S² fulcrumed at S³ upon the 70 table T.

A movable bottom U is adapted to slide 75 into position beneath the mould S', when said mould is in the closed position as shown in Fig. 2, through the medium of suitable mechanism described hereinafter. This sliding bottom U is provided with a chamber U' connected by a pipe U² with a convenient vacuum pump.

V is a blank mould made in two sections and 80 adapted to be raised and lowered in any convenient manner, a particular mechanism for this purpose being described hereinafter. This blank mould V is adapted for air tight connection with the neck mould I for the purposes to be more clearly brought out herein- 85 after.

90 W is a supporting table located over the receptacle containing the molten glass W' and carrying knives X adapted to be brought together by suitable mechanism.

95 The perforated bottom U is attached to a slide U³ moving in a slide way T' of the table T. This slide has an opening U⁴ of a proper size to allow the piston rod G and the neck mould I to pass there-through. The slide U³ 100 has a pin U⁵ working in a cam groove U⁶ in a suitable part attached to the shaft Z. This shaft is provided with another cam member, having a groove Z', which operates on a rod 1 attached to a cross head 2, and suitably 105 guided so as to reciprocate in the same direction as the slide U³. To the cross head 2 are pivoted links 3, which are connected with the arms S² of the mould casing S, pivoted at S³ as hereinbefore stated. The two cam grooves 110

U^4 and Z' are so arranged that when the finishing mould is closed, the bottom U will be in registry with the sections of the mould, but when the mould is open, the opening U^4 will be in axial alignment with the piston rod G .

The blank mould V (see Figs. 6, 9 and 10,) consists of two sections having lips V' which when the mould is closed fit around vertical rods 4 along which the blank mould is adapted to slide up and down. Each of the mould sections is provided with an outwardly extending bolt V^2 , each having a nut V^3 . These bolts are engaged loosely by arms 5 which are fulcrumed at 6 and carry or support the mould sections, which are guided rectilinearly by a suitable member, such as the rib 9^a . The arms 5 are moved inward or outward, carrying the blank mould sections in a like direction, by means of rods 7 projected from pistons 8 , suitable nuts or other abutments being provided on each piston rod at each side of the respective arms 5 . The pistons 8 are arranged within a cylinder 9 , and are pressed toward each other as shown in Figs. 9 and 12, as long as compressed air from the pipe 11 (connected with the inlet E at the top of the cylinder A) enters the cylinder 9 through a port 10 (Figs. 10 and 12) having branches leading to the ends of the cylinder.

When the pistons are in this position, they close ports 12 leading from the cylinder 9 to a pipe 13 which is connected with the inlet D at the lower end of the cylinder A . At the center of the cylinder 9 is located another air inlet port 14 , which is connected, by a pipe 15 , with the outlet 16 of a cylinder 17 , containing a piston 18 . This piston is connected by a piston rod 19 with toggle links 20 , connected with levers 21 , fulcrumed at 22 . With the other ends of the said levers are connected links X^2 , pivotally attached to the knives X mounted to slide in suitable guideways X' . The cylinder 17 has two inlets 23 and 24 respectively at its opposite ends. The inlet 23 is connected with a source of compressed air supply, together with the inlet E of the cylinder A and the inlet 10 of the cylinder 9 , as indicated in Fig. 6. The inlet 24 is connected by a pipe 25 with a port 26 in a cylinder 27 . This cylinder contains a piston 28 which by means of a rod 29 engages and is adapted to lift the cylinder 9 and the parts connected therewith, among them the blank mould V . The cylinder 27 has a compressed air inlet 30 at its lower portion.

It will be understood that flexible or other loose connections will be provided in the pipes 11 , 13 and 15 so as to preserve the connection of the cylinder 9 with said pipes during the upward and the downward movements of said cylinder.

The port 30 is connected with the source of compressed air permanently, while the connection of the ports E , 10 and 23 with the source of compressed air is made and inter-

rupted at the times specified hereinafter. The diameter of cylinder A should be larger than that of cylinder 27 .

It will be understood that when the machine is at rest, compressed air entering the cylinder 27 at 30 will hold the piston 28 and, through its intermedium, the cylinder 9 and blank mould V , in the upper position shown in Figs. 2 and 10. At the same time, compressed air passing from the port 26 of the cylinder 27 through the pipe 25 to the port 24 of the cylinder 17 will have shifted the piston 18 to the left, causing the knives X to close toward each other. Furthermore, the air entering the cylinder 17 at 24 will have passed from the port 16 through the pipe 15 to the central inlet 14 of the cylinder 9 , thus causing the pistons 8 to move apart, and the blank mould V to open. At the same time, since in moving apart the pistons 8 have uncovered the ports 12 , the air entering at 14 will have reached the pipe 13 and through it the inlet D at the bottom of the cylinder A , causing the piston F , head H , and neck mould I to rise. As soon as the piston F clears the by-pass B' as shown in Fig. 2, the air passing up through B' will lift the piston J and plunger M . The compressed air passes from the cylinder A through the openings G' into the hollow piston rod G and closes the valve N . The ports E , 10 , and 23 are disconnected from the source of compressed air, and the connections of the vacuum pump or other suction device with the pipes R^2 , U^2 , are likewise interrupted. The finishing mold S' and the slide U^3 for the mould bottom U are in the position illustrated by Fig. 8.

To recapitulate, the position of rest of the several parts is as follows: The pistons F , J and the parts connected therewith (neck mould I , plunger M) are raised as shown in Fig. 2; the valve N is closed as shown in Fig. 4; the finishing mould S' is open and its bottom U moved aside as shown in Fig. 8, while the opening U^4 aligns with the axis of the pistons F , J ; the blank mould V is raised and open, and the knives X are closed below the blank mould.

To start the operation, air is admitted simultaneously or about so to the inlets E , 10 and 23 . The admission of air at the latter port causes the piston 18 to be moved to the right and thus opens or separates the knives X by means of the toggle links 20 and levers 21 . The entrance of air at the inlet 10 causes the pistons 8 to move together as shown in Fig. 12, thus closing the blank mould V as shown in Fig. 9. The air flowing into the extension B of the cylinder A first presses down the piston J only, so as to cause the plunger M to be projected downwardly beyond the head H , this relative position being shown in Fig. 1. The movement of the pistons 8 toward each other has closed the ports 12 and thus disconnected the port 13 .

D at the bottom of the cylinder A from the compressed air supplied through the inlet 30. There is therefore no counter-pressure in the lower part of the cylinder A, and the pistons 5 J and F, after coming together, move downward in unison until the neck mould I engages the blank mould V. Then the blank mould is forced downward owing to the fact that the diameter of the piston F is larger than that 10 of piston 28, so that there is a preponderance of pressure on the piston F. The neck mould I, head H, and piston rod G pass through the opening U⁴ of the slide U³, and the blank mould passes through the table W into the 15 molten glass W', this being the position of parts shown in Fig. 1. Connection is then established between the pipe R² and the vacuum pump or other suction device. Inasmuch as the openings G' of the piston rod G 20 are in communication with the chamber R', see Fig. 1, air will be sucked out through the openings P and Q (Fig. 3) lifting the valve N, and exerting a suction within the blank mould V, it being understood that the plunger M fits loosely in the bottom plate of the 25 head H. The glass is thus sucked up into the blank mould V as shown in Fig. 1, and drawn forcibly against and around the plunger M and against the head H and neck mould 30 I. The material is thus driven into the neck mould with considerable force and perfectly shaped therein. Thereupon the supply of compressed air to the inlets E, 10 and 23, is interrupted. The downward pressure 35 on the piston F and on the blank mould V having ceased, the upward pressure of the air admitted to the cylinder 27 through the inlet 30 will cause the piston 28 to rise, lifting the blank mould V together with the neck mould I 40 and the other parts resting on the blank mould, through the medium of the head H and piston rod G. When the piston 28 and the blank mould V have risen to the position shown in Figs. 2 and 10, air will pass from 45 the outlet 26 through the pipe 25 to the port 24 of cylinder 17, and will thus drive the piston 18 over to the position shown in Figs. 9 and 10. This will cause the knives X to move toward each other below the blank 50 mould V and to cut off any glass adhering to the bottom of said mould. As the piston 18 uncovers the port 16 of the cylinder 17, air will pass from the pipe 25 to the pipe 15 and to the port 14 of cylinder 9. This will cause 55 the pistons 8 to move apart, separating the blank mould sections. The upward movement of the blank mould V has raised the neck mould I and the parts connected therewith only a portion of their upstroke. The re- 60 mainder of the upward movement of these parts is brought about as follows: When the pistons 8 move apart to open the blank mould V, they allow air to pass from the inlet 10 through the pipe 13 to the inlet D at the bottom of the cylinder A. The air lifts the pis-

ton F and the parts connected therewith. The blank adhering to the neck mould I is thus raised into the finishing mould S', which is still in the open position illustrated by Fig. 1. As soon as the openings G' enter the cylinder A, compressed air flowing into the hollow piston rod G will close the valve N. As the area of the said valve and of the cage L is smaller than that of the piston F, the upward pressure on the piston will prevail. 70 In order to enable the said piston to start readily from its lower position, such piston is beveled or rounded at its edge so that the air will get under it, and a like construction is employed for the pistons J and 28. 75

When the piston F at the end of its upstroke uncovers the by-pass B', the compressed air will pass into the extension B and raise the upper piston J, and with it the valve cage L, so as to withdraw the plunger M from the neck of the glass blank, as shown in Figs. 2 and 4. The bottom U is then slid under the blank, and the finishing mould S' is closed, these parts taking the position shown in Figs. 2 and 7. Suction through the pipe R² is then discontinued, and applied through the pipe U², so as to produce a vacuum in the chamber U'. This chamber being in communication with the casing S, and the mould S' as well as the upper wall of the chamber U' being perforated, the air entering the glass blank either through imperfect joints or through a valve H' to be described presently, causes the glass to expand to the sides and bottom of the finishing mould, which of course corresponds to the shape of the article it is desired to form. In the present illustration this article is a bottle, but it is to be understood that all kinds of hollow glass ware may be made according to my process. 95

When the article is small, sufficient atmospheric air will generally enter through imperfect joints. Where the leakage is insufficient, I may provide a special suction valve H', as shown in Figs. 3 and 11, opening inwardly and communicating with an annular chamber H² of the head H. This chamber is so arranged that during the first operation of drawing the glass into the blank mould, the valve cage L shuts off said chamber H² from communication with the space in which suction is created. When the valve cage has been raised, as in Fig. 2, the chamber H² is open to the interior of the piston rod G, and thus air may enter through the valve H' into the bottle, which is being pressed outwardly against the perforated finishing mould S' by the suction applied on the outside of said mould. 110

When the article has been formed in the 115 manner just described, the two parts of the mould casing S and the mould S', are separated, or, in other words, the finishing mould is opened, after which the neck mould I is opened and the finished article removed. 120 130

After the article has been removed, the sliding bottom U is again moved aside (Fig. 8) to allow the parts carried by the piston rod G to descend and repeat the operation, 5 as hereinbefore described.

It will thus be seen that in using my process, suction is successively applied in opposite directions, that is, suction is first used to force the glass toward the neck of the bottle 10 (in the present illustration) so as to mould the said neck which is generally beaded, and then suction is applied from the outside, while atmospheric air has access to the inside of the article, for the purpose of expanding said article toward the bottom of the bottle. The material is therefore subjected successively to opposite strains.

In Fig. 11 I have shown a slight modification in the construction of the piston rod G and valve cage L. These parts are substantially the same as in Fig. 4, but in the inner wall of the piston rod G I have added a longitudinal groove G², which is slightly longer than the valve-cage L. The operation in this case will be substantially the same as above described, differing only in the following particular:—When compressed air is admitted to the cylinder A at D, and the pistons F and J rise together, the neck mould I 25 with the blank adhering thereto, will be lifted as before described. When the piston F reaches the top of the cylinder A, and compressed air passes through the by-pass B' to the extension B, the piston J is lifted further 30 and the valve cage L is thus caused to move upward within the piston rod G. At the moment that the lower end of the valve cage L gets above the lower end of the groove G², compressed air from the upper part of the 35 hollow piston rod G will pass through the said groove G² to the lower end of said piston rod and into the hole which has been formed in the blank by the plunger M. This puff of compressed air will cause the hole formed by 40 the withdrawal of the plunger to be expanded, as will be understood by comparing the showing in Fig. 4 with that in Fig. 11. This expansion of the cavity facilitates the 45 finishing of the blank in the mould S'. This operation involving an enlargement of the cavity formed by the plunger M, is recommended for hollow articles of relatively large size.

It will be observed that in both species of my invention described hereinbefore, the narrow end or neck of the blank is directed upward during the entire operation, so that the influence of gravity is always in the same direction and all side strains and injury are 50 avoided that might be caused by inverting the blank during the process of manufacture. As the position or direction of the blank remains the same (that is, with the neck pointing in the same direction) during both suction operations, the blank is subjected sim-

ply to longitudinal strains exerted successively in opposite directions and a uniform action of both forces is the result, with a regular shaping of the article. The two suction operations are upward and downward respectively and the injection of air, is downward in the second example or species described. These features however need not all be employed conjointly, as various modifications may be made without departing 70 from the nature of my invention as defined in the claims.

I claim and desire to secure by Letters Patent:

1. A process for manufacturing hollow 80 glassware, which consists in shaping a glass blank by suction exerted in one direction and at the same time piercing said blank a part of its length and then applying suction in the opposite direction to expand and finish said 85 blank.

2. A process for manufacturing hollow 90 glassware, which consists in gathering a glass blank by suction and at the same time shaping and piercing said blank, and then applying suction to the exterior of said blank to expand it.

3. A process for manufacturing hollow 95 glassware, which consists in shaping a glass blank by suction exerted toward one end of the blank, and then exerting external suction toward the other end of the blank to expand the blank.

4. A process for manufacturing hollow 100 glassware, which consists in shaping a glass blank by suction exerted toward the narrow end or neck of the blank so as to compress the material at said neck, and then exerting external suction toward the other end or bottom end of the blank.

5. A process for manufacturing hollow 110 glassware, which consists in shaping a hollow glass blank by suction exerted toward one end of the blank and at the same time piercing the said end of the blank, and then exerting external suction toward the other unpierced end of the blank so as to expand the blank.

6. A process for manufacturing hollow 115 glassware, which consists in shaping a glass blank by suction exerted toward one end of the blank and at the same time piercing said end of the blank, then blowing a fluid under pressure into the pierced end of the blank so as to enlarge its cavity, and thereupon applying external suction to expand the blank.

7. A process for manufacturing hollow 125 glassware, which consists in shaping a glass blank by suction exerted toward the narrow end or neck of the blank, introducing a fluid under pressure into said end of the blank, and thereupon expanding the blank by external suction exerted toward the other end of the blank.

8. A process for manufacturing hollow 130

glassware, which consists in forcing a body of plastic glass by suction toward one of its ends, so as to compress and shape said end into blank form and then introducing a fluid under pressure into said end of the blank and expanding the blank by external suction exerted toward the other end of the blank.

9. A process for manufacturing hollow glassware, which consists in forcing a body of plastic glass by suction toward one of its ends so as to compress and shape said end into blank form and at the same time piercing it, and then blowing a fluid under pressure into the pierced end of the blank and applying external suction toward the other end of the blank to expand it.

10. A process for manufacturing hollow glassware, which consists in subjecting a body of plastic glass to suction exerted successively toward opposite ends, first in one direction to shape one end of the blank, and then in the opposite direction to expand the blank toward its other end.

11. A process for manufacturing hollow glassware, which consists in shaping a glass blank by suction exerted upward toward the neck of the blank, and then exerting a downward external suction toward the other end or bottom end of the blank.

12. A process for manufacturing hollow glassware, which consists in subjecting a body of plastic glass to suction exerted successively toward opposite ends, one of the suction operations being directed upward, and the other downward, and the same end of the glass body being at the top during both operations.

13. A process for manufacturing hollow glassware, which consists in subjecting a body of plastic glass to suction exerted successively toward opposite ends, to first shape one end of the blank and then expand the blank toward its other end, the same end of the blank pointing in the same direction during both operations.

14. A process for manufacturing hollow glassware, which consists in subjecting a

body of plastic glass to suction exerted upward to shape the neck of the blank, and then exerting a downward external suction toward the other end or bottom end of the blank, the neck end of the blank being directed upward during the entire process of manufacture.

15. A process for manufacturing hollow glassware, which consists in shaping a glass blank by upward suction toward the neck end of the blank and then introducing a fluid under pressure downward into said end of the blank and expanding the blank by external suction exerted downward toward the other end of the blank.

16. A process for manufacturing hollow glassware, which consists in shaping a glass blank by upward suction toward the neck end of the blank and at the same time piercing said end, and then injecting a fluid under pressure downward into the pierced end of the blank and expanding the blank toward its other end by downwardly directed external suction.

17. A process for manufacturing hollow glassware, which consists in drawing and forming a blank by suction upward from a mass of molten glass, and then exerting a downward suction externally on said blank to expand and finish it.

18. A process for manufacturing hollow glassware, which consists in withdrawing a body of glass by suction from a mass of molten glass and simultaneously shaping one end of said body by exerting the suction toward the neck of the blank, and then exerting an external suction toward the other end or bottom of the blank to expand and finish it.

In testimony whereof, I have hereunto set my hand in the presence of two subscribing witnesses.

CHARLES F. COX.

Witnesses:

ARTHUR C. MULFORD,
WM. S. FITHIAN.
